(57) **CLAIM**

The ornamental design for a golf hole cup, as shown and described.

DESCRIPTION

FIG. 1 is a perspective view of a golf hole cup.

FIG. 2 is a perspective view of the golf hole cup of FIG. 1 showing an inserted fragmented environmental flag stick.

FIG. 3 is a top view of the golf hole cup of FIG. 1; and,

FIG. 4 is a left side view of the golf hole cup of FIG. 1 of which the right side view, front view and back view are mirror images thereof.

The broken lines shown in the figures form no part of the claimed design.

1 Claim, 4 Drawing Sheets
